UNITED STATES PATENT OFFICE.

ARTHUR J. SARGENT, OF PROVIDENCE, RHODE ISLAND.

DEVICE FOR LOCATING AND RAISING SUNKEN SHIPS.

Application filed June 3, 1925. Serial No. 34,704.

To all whom it may concern:

Be it known that I, ARTHUR J. SARGENT, a citizen of the United States, residing at Providence, in the county of Providence and State of Rhode Island, have invented certain new and useful Improvements in Devices for Locating and Raising Sunken Ships, of which the following is a specification.

10 This invention relates to an apparatus by the use of which sunken vessels may be easily located and brought to the surface of the water, and one object of the invention is to provide an apparatus which is so associated with the vessel that, when the vessel sinks, air may be forced into the compartments provided therein and water which may have accumulated in these compartments expelled so that the vessel may of its own buoyancy 20 rise to the surface of the water.

Another object of the invention is to provide a vessel having an arrangement of inlet and outlet pipes which will permit air to be forced into the normally water-tight compartments of the vessel and permit air to escape from these compartments if the pressure is too great.

Another object of the invention is to provide an improved arrangement of feed pipes and a mooring line which will be normally stored upon the upper deck of the boat and a float which will be connected with the mooring line and feed pipes and so deposited upon the upper deck that, when the vessel sinks, this float may move upwardly through the water to the surface thereof and draw the mooring line and feed pipes with it. By this arrangement the salvage tug can be secured to the mooring line and the feed pipes drawn aboard the tug and connected with air pumps.

This invention is illustrated in the accompanying drawings, wherein

Figure 1 is a view showing a sunken vessel in longitudinal section and the mooring line and feed pipes drawn upwardly to the surface of the water by the float;

Fig. 2 is a top plan view showing the float resting in its cradle upon the deck and the mooring line and feed pipes in their normal stored positions, and

Fig. 3 is a view taken longitudinally through the upper deck of the vessel and showing the float, mooring line reel and feed

pipe container in side elevation, a portion of 55 the feed pipe container being broken away.

This apparatus is for use in connection with any boat of a conventional construction which is provided with the usual water-tight compartments. Referring to Fig. 1, the boat 60 is indicated in general by the numeral 1 and the boat has been shown divided into a number of compartments 2 which are normally 65 water-tight and divided from each other by bulk heads and decks of a conventional construction. The number of compartments provided will, of course, be controlled by the size of the vessel. When a leak is caused by a collision, water will enter the hull below the water line and if a sufficient number 70 of the compartments become flooded, the normal buoyancy of the vessel will be overcome and the vessel will sink. If the water which has accumulated in these compartments can be expelled from them, the normal 75 buoyancy of the vessel would then be restored and it would rise to the surface.

There has, therefore, been provided a number of air inlet pipes 3 which extend longitudinally in the vessel, as shown in Fig. 1, 80 and are provided with outlets 4. These outlets are spaced from each other longitudinally of the pipes and are so located that air 85 may be supplied to the various compartments into which the boat is divided. Each 85 of the outlets is in the form of a check valve which may be opened by air forced through the pipe but will be normally closed so that air cannot pass into the pipes from the compartments. Pipes 5 extend upwardly from 90 the pipes 3 through the upper deck of the vessel and each has its upper end connected with a feed pipe 6. The feed pipes 6 are 95 preferably strong rubber hose which may be coiled in the housing or container 7 located 95 upon the deck and firmly secured thereon by the brackets 8. Since the feed pipes 6 are formed of rubber hose, they may be packed in a compact mass in the container 7 and when necessary can be readily drawn outwardly and upwardly through the top of the container.

It is important that provision be made for the release of excess air pressure in the compartments and, therefore, there has been provided a number of pipes 9 which extend upwardly from the various compartments and through the upper deck of the vessel.

At the upper end of each pipe 9, there has been provided a check valve 10 which will be of a conventional construction and permitted of being set so that it may of itself open when the pressure in the compartment from which its pipe 9 leads exceeds a certain point. These valves 10 should further be so constructed that they may be manually opened at will in case the vessel 10 does not come to the surface upon an even keel. The pipes 9 communicate with the compartments through the bottoms thereof and as the air is admitted into the upper portions of the compartments, it will be obvious that as air accumulates in the upper portions of the compartments it will serve to force the water out of the compartments through the pipes 9. Therefore, a sufficient number of the compartments may 15 be cleared of water in order to permit the vessel to rise to the surface.

The mooring line 11 may be a strong rope or wire cable and is wound upon a drum 12. The drum 12 is provided with an axially disposed shaft 13 which extends beyond the ends of the drum and is journaled in the upstanding arms 14 of a bearing bracket 15. This bracket 15 rests upon the deck in spaced relation to the feed pipe container 30 7 and is firmly secured by bolts or other suitable fasteners 16. Blocks 17 are secured upon the deck between the bracket 15 and container 7 and serve to form a cradle in which the float 18 normally rests. This 35 float 18 may be formed of any suitable material but will preferably be a hollow airtight box or cylinder formed of heavy sheet metal. At one end the float carries a chain 19 to which the mooring line 11 is secured and at its other end the float carries an eye 20 to which a chain 21 is secured. The chain 21 has its other end firmly secured to the free ends of the feed pipes 6, as shown in Fig. 2. From an inspection of 40 Figs. 2 and 3, it will be readily seen that, when the vessel sinks to the position shown in Fig. 1 and the float 18 rises to the surface of the water a pull will be exerted upon the mooring line 11 and feed pipes 50 6 which will cause them to be drawn upwardly to the surface of the water with the float. The float in addition to serving as means to draw the mooring line and feed pipes upwardly to the surface of the water will also serve as means to indicate the 55 position of the sunken vessel so that a tug which has been sent out to look for a missing vessel can readily locate the same. When the tug has located the float, the float 60 will be caught by means of a suitable grapple and drawn aboard the tug. The mooring line will be made fast to a cleat upon the tug and the tug will be firmly anchored so that it cannot drift away from a position above the boat. The feed pipes

will then be connected with air pumps with which the tug will be provided and air forced through the pipes 6 into the pipes 5 through which it will pass into the pipes 3 and out through the outlet valves 4 into the 70 compartments of the sunken vessel. As the air is forced into these compartments, it will gradually displace the water which has accumulated in them, the water being forced through the pipes 9. As soon as a sufficient 75 quantity of water has been displaced, the natural buoyancy of the vessel will cause it to rise to the surface. If the vessel comes to the surface on an even keel, it is then only necessary to connect the vessel with the 80 rescue tug by means of a tow line and the vessel can be towed into port. If, however, the vessel should come to the surface bow first or stern first, this will indicate that there is more air in the compartments 85 at one end of the vessel than at the other end. The valves at the upper ends of the pipes 9 which extend through the deck at the higher end of the vessel will then be opened and a sufficient amount of air allowed to escape to cause the elevated end 90 of the vessel to gradually sink and the low end to rise. There is no danger of too much air being forced into the compartments and causing the plates or planking of the vessel 95 to give way as the valves 10 will be set to open at a predetermined pressure and permit surplus air to escape.

Having thus described the invention, I claim:

1. The combination with a boat having compartments normally water-tight, of air inlet pipes mounted in said boat and having valve-controlled outlets to deliver air into said compartments, said pipes having their inlet ends extended externally of said boat, feed pipes connected with the inlet ends of said air inlet pipes, a float connected with said feed pipes, outlet pipes leading from said compartments to a point externally of 105 said boat, and control valves at the outer ends of said outlet pipes.

2. The combination with a boat having compartments normally water-tight, of an air inlet pipe extending from a point externally of the boat into said compartments and provided with valve-controlled outlets to deliver air into the compartments, outlet pipes leading from said compartments and extended externally of the boat and at their outer ends provided with control valves, a supply pipe connected with the outer end of said inlet pipe and adapted to be drawn upwardly from a sunken boat to the surface of the water, and a float connected with said supply pipe.

3. The combination with a boat having compartments normally water-tight, of an air inlet pipe extending from a point externally of the boat into said compartments 130

and provided with valve-controlled outlets to deliver air into the compartments, outlet pipes leading from said compartments and extended externally of the boat and at 5 their outer ends provided with control valves, a supply pipe connected with the outer end of said inlet pipe and adapted to be drawn upwardly from a sunken boat to the surface of the water, a mooring line, a carrier for said mooring line secured upon said boat and adapted to have the mooring line extended therefrom, and a float connected 10 with said mooring line and supply pipe.

4. The combination with a boat having 15 compartments normally water-tight, of an air inlet pipe extending into the boat from a point externally thereof and into said compartments, said pipe being provided in the compartments with outwardly opening 20 check valves, a flexible feed pipe connected with the outer end of said inlet pipe, a carrier for said supply pipe secured upon said boat, a mooring line, a carrier for said mooring line secured upon said boat, and a float 25 connected to said feed pipe and mooring line and adapted to move upwardly from

the boat to the surface of the water when the boat sinks and draw the feed pipe and mooring line upwardly.

5. The combination with a boat having 30 compartments normally water-tight, of an air inlet pipe extending into the boat from a point externally thereof and into said compartments, said pipe being provided in the compartments with outwardly opening 35 check valves, a flexible feed pipe connected with the outer end of said inlet pipe and adapted to be coiled upon the deck of the boat, an enclosure for the coiled supply pipe secured upon the deck of the boat, a drum means to 40 rotatably mount said drum secured upon the deck of the boat, a mooring line wound upon said drum and having one end secured thereto, a cradle upon said boat deck, and a float normally resting in said cradle and 45 connected with said supply pipe and mooring line and adapted to draw the mooring line and supply pipe upwardly to the surface of the water when the boat sinks.

In testimony whereof I affix my signature. 50

ARTHUR J. SARGENT. [L. s.]
